CLAIM

The ornamental design for a southwestern bed, as shown and described.

DESCRIPTION

FIG. 1 is an elevational view of the front side of a southwestern bed showing my design, including extended corner posts shown partially cutout for ease of illustration;
FIG. 2 is an elevational view of the back side thereof;
FIG. 3 is an elevational view thereof taken from the right side, the elevational view from the left side being the same;
FIG. 4 is a top plan view thereof; and,
FIG. 5 is a perspective view thereof.

The inside of the footboard not shown is not part of the claimed design.
